UNITED STATES PATENT OFFICE

LOUIS GILLON, OF LES LILAS, NEAR PARIS, FRANCE.

MACHINE FOR CARDING BUTTONS BY MEANS OF ELECTRICITY.

SPECIFICATION forming part of Letters Patent No. 296,401, dated April 8, 1884.

Application filed January 7, 1884. (No model.) Patented in France March 8, 1883, No. 154,186, and in Belgium March 10, 1883, No. 60,710.

To all whom it may concern:

Be it known that I, LOUIS GILLON, of the city of Les Lilas, near Paris, France, have invented an Improved Machine for Carding Buttons by Means of Electricity, (for which I have obtained a patent in France for fifteen years, No. 154,186, dated March 8, 1883, and in Belgium for fifteen years, No. 60,710, dated March 10, 1883,) of which the following is a full, clear, 10 and exact description.

This invention relates to a machine for carding metal-shank buttons, and is based upon the application of the attractive force developed in the core of an electro-magnet by the passage of 15 an electric current to effect the distribution of the buttons in their proper positions upon the cards, which are fed up to the machine continuously or intermittently.

In order that the invention may be more 20 readily understood, I have represented examples of the machine in the accompanying drawings, wherein—

Figure 1 represents a side elevation, and Fig. 2 is a top plan, of the machine, which is double- 25 acting. Fig. 3 is an end elevation of the machine.

In these figures the same letters of reference indicate the same parts.

The buttons are first placed in chutes *a*, of 30 which the center one only is shown in the drawings, the others being only indicated by their center lines. In the machine here represented there are two sets of chutes *a*; but there may be a single set only. Each set comprises nine chutes, by preference, corresponding 35 to the nine buttons of each line on the card. The chutes *a* are of such form and at such an inclination that the buttons placed therein have a tendency to roll upon them- 40 selves until the shank, by opposing this rotation, acquires a forward position. The regular descent of the buttons is insured by a jarring motion imparted by a wiper-wheel, *b*, and rods *c*, on which rods the upper parts of the chutes 45 are supported. The buttons of each file are distributed one by one to the lower part of the chute by two vertically-movable pins, *d*, which are raised whenever it is necessary to allow of the card changing its position to receive a new row of buttons. Two other pins, 50

e, separated from the pins *d* by the extent of a button, then rise to separate the one in front from those that follow and prevent their descent. These pins *d* and *e* are carried upon separate cross-bars *f*, actuated by cams *h* and 55 by the medium of the arms *4* and *5* and rods *6* and *7*. The first button of each file is brought exactly over a hole made in the card by the attraction of the iron shank of the button by the pole-piece of a magnet or electro-magnet 60 excited by a current from a battery or other generator. This electro-magnet is shown in Fig. 3, and will be described hereinafter. When the current passes, each button is poised upon its shank above the corresponding hole 65 in the card, and the nine buttons are simultaneously pressed by the cross-bar *i*, which is slightly hollowed opposite each button.

To increase the attractive effect of the pole-piece *j* of the electro-magnet *k*, and in order 70 that this attraction may be uniformly distributed from one end to the other, the pole-piece is notched, so as to present opposite each hole in the card, and consequently opposite each button, a tooth or stud, at the extremity 75 of which the magnetic effect which acts on the button is developed. The cross-bar *i* is actuated by the cams *x* through the medium of rods *l*. The electric communication is established at and for the duration of time required by means of a commutator, *m*, whose periphery is composed partly of vulcanite or other insulating material, and against which rubs a brush, *n*. The circuit is broken when the brush *n* touches the insulating portion, and 85 is completed when it makes contact with the metallic portion of the commutator, at which moment the button is attracted and poised upon its shank opposite the holes in the cards, and retains it in that position until forced into 90 place by the pressure of the cross-bar *i*. The cards are fed up by means of chains or bands, upon which they are fixed by small spring-blades like paper-clips, or in any other suitable way.

In order to bring the holes in the cards opposite the projecting studs of the pole-piece *j*, the cam *o* actuates through the lever *p* and the rod *q* a pawl, *r*, which moves to the extent of five teeth of a ratchet-wheel, *s*. The pawl 95

- is held back by a pin, *t*, which allows it to engage only with every fifth tooth. (See Figs. 4 and 5.) The pin *t* is raised for the passage of each successive card by means of a cam 5 made in three parts and formed on the face of the wheel *s*. The carriage *u*, in which the chain or band wheel shaft is mounted, is adjustable for regulating the tension of the band or chain, as will be readily understood.
- 10 *v* is a plate to support the cards under the weight of the buttons and the pressure exerted on them by the cross-bar *i*.
- 15 1, 2, and 3 are gear-wheels for transmitting rotary motion to the wheel *b*.
- 20 The levers 4 and 5 and the rods 6 and 7 are for transmitting motion from the cams *h* to the pin-bars *f*.
- 25 The rods 8 serve to regulate the inclination of the chutes *a*, and the curved bars 9 support them at the upper part. The buttons, being placed in the chutes, are jarred downward therein until the lower row reaches the raised pins *d*. Then the pins *e* are raised and the pins *d* lowered to let the lower row of buttons

descend farther until their shanks are aligned 25 with the holes in the card, and they are then subjected to the action of an electro-magnet and of the cross-bar *i*, in manner already described. The card is then moved to bring another row of holes in position, the pins *d* are 30 raised, the pins *e* lowered, and the operation is then continued, as before stated.

I claim—

The combination of the chutes *a*, pins *d e*, electro-magnet *k*, notched pole-piece *j*, and 35 bar *i* with mechanism, substantially as described, for moving the pins *e* and the bar *i*, and for moving a card over the notched pole-piece and under the bar *i*, substantially as herein shown and described.

40 The foregoing specification of my improved machine for carding buttons by means of electricity signed by me this 17th day of November, 1883.

LOUIS GILLON.
